United States Patent Office.

G. L. MERRILL, OF CHICAGO, ILLINOIS.

Letters Patent No. 67,180, dated July 23, 1867.

IMPROVEMENT IN MACHINE FOR CLEANING AND ASSORTING CRANBERRIES.

The Schedule referred to in these Letters Patent and making part of the same.

TO ALL WHOM IT MAY CONCERN:

Be it known that I, G. L. MERRILL, of Chicago, in the county of Cook, and State of Illinois, have invented a new and useful Improvement on Machine for Assorting and Cleaning Cranberries; and I do hereby declare that the following is a full, clear, and exact description of the construction and operation of the same, reference being had to the annexed drawings and letters of reference marked thereon, making a part of this specification, in which—

Figure 1 is a perspective representation of my machine.

The nature of my invention relates to cleaning the dirt from cranberries, and separating the soft and imperfect ones from those which are sound, by means of the momentum of the berries passing down an inclined plane and falling into separate apartments, made such a distance from the lower end of the inclined plane that the assorted berries will fall into their respective places. This I accomplish by means of an adjustable chute-board placed on the top of the box, and so arranged that it can be set at such an angle as will cause the berries to pass over the board with such momentum as the condition of the berries may require, in order that the process of cleaning and separating may be properly done; and in providing what I term a movable finishing-board, which is adjusted in that part of the box in which the sound berries fall, and has on its top a peculiar-shaped movable stop, which is used to prevent the berries from falling off from the board when cleaning the last run of refuse berries among which but few are good.

It is well known to those versed in cranberry culture that a small quantity of soft or rotten berries soon materially injures the balance of those in the barrel; and as no suitable device has heretofore been used for separating imperfect berries, I claim that my machine is of important public utility, for the berries can be nicely and speedily cleaned and separated, rendering the sound berries much more valuable than the entire lot before being run through the machine.

To enable others to make and use my machine, I will describe its construction and operation.

A represents the substantial box, which should be made water-tight at the bottom. The front side of this box is broken away in order to give a clear view of the partitions and other arrangements on the inside; B shows the chute-board, having the sides M, upon which the berries are put when they are to be cleaned. The sides M are hung to the sides of the box A by means of the pins P, and the bottom B rests upon the cross-piece R, placed transversely across the top of the box A, and held in place by means of the pins S, passing down into the edges of the box. The cross-piece R can be moved nearer to the front of the machine if desired, and secured by putting the pin s into the hole t, in which case the chute-board will have a less inclination, and as a consequence the berries will pass more slowly into the box A. Any number of holes, t, may be made in the box A necessary to give the required angle to the board B. D is the first partition used in separating the berries, and is attached to the reverse-inclined board C, upon which the worthless berries fall. E represents the second partition, extending down to the bottom of the box A. Both good and poor berries fall between partitions D E and are received into the part F, from which they can be removed by raising the front-end board J, as seen by the dotted lines z; and recleaned. All of the berries which pass over the partition E, and into the part G I, will be found suitably cleaned. K represents the finishing-board, supported by the skirting L and short standards placed under each end. The dotted lines z show the position of the one on the front side. This board can be moved to or from the partition E, as most convenient for cleaning the refuse berries at the last of the run. N is the movable stop which is used to prevent the soft berries from passing over the lower end of the board K at W. V shows a tongue or projection upon which the berries rest and prevent the stop from falling off from the board K during the process of cleaning.

Operation.

The berries can be put in small quantities upon the board B, and the berries will be separated as above described. The parts N K L may be removed from the division G I, when running the berries through the first time, and after the sound berries have been removed, the board K can be set in the box A for the cleaning of the last run. The sliding stop N can be moved so as to give as much or little surface of the board K as desired, or according to the amount of refuse berries to be cleaned.

Having thus fully described my device, what I claim, and desire to secure by Letters Patent of the United States, is—

1. The arrangement and combination of the adjustable chute-board B M, partitions D E, and reverse board C, substantially as and for the purpose set forth.
2. The combination of the board K and movable stop N, when constructed as and for the purpose specified.
